UNITED STATES PATENT OFFICE.

LAWRENCE HENRY TAYLOR, OF RED CLOUD, NEBRASKA.

TIE-HOLDING ATTACHMENT FOR COLLARS.

1,209,348.

Specification of Letters Patent. Patented April 20, 1911.

Application filed October 23, 1910. Serial No. 192,150.

To all whom it may concern:

Be it known that I, LAWRENCE H. TAYLOR, citizen of the United States, residing at Red Cloud, in the county of Webster and 5 State of Nebraska, have invented certain new and useful Improvements in Tie-Holding Attachments for Collars, of which the following is a specification.

My invention relates to new and useful 10 improvements in neckwear and more particularly in men's collars, the primary object of my invention being the provision of a tie holding attachment in the form of one or more tabs disposed to engage a necktie and hold it in place so that it will not slip 15 out of position and expose the collar button.

More specifically my invention is particularly adapted to collars of the turn-over type and the tabs are formed on or carried 20 by the inner fold of the collar at either side of the collar button receiving flaps and are arranged to support the tie against downward movement past the collar button when the collar and tie are in place.

With these and other objects in view, my 25 invention will be more fully described, illustrated in the accompanying drawings and then specifically pointed out in the claims which form a part of this application.

In the drawings:

Fig. 1 is a perspective view of a collar constructed in accordance with my invention;

Fig. 2 is a sectional view taken on the line 30 2-2 of Fig. 1;

Fig. 3 is a perspective view of a modified form of collar construction;

Fig. 4 is a fragmentary view of a further form of my invention.

Corresponding and like parts are referred 40 to in the following description and indicated in all the views of the drawings by the same reference characters.

In Fig. 1 I have illustrated my invention 45 as applied to a turn-over collar 10 of conventional style and of the water-proof type provided at its forward ends with overlapping flaps 11 having button holes 12.

The inner fold 13 of the collar adjacent 50 the inner portions of the flaps 11 is formed near each flap with one or more U-shaped clefts 14 the base portions of which are parallel to the lower edge of the collar and the sides of which extend toward the top 55 of the collar. The substantially rectangular-shaped tongues 15 thus provided are bent

outwardly and upwardly, as best shown in Fig. 2 of the drawings to provide hooks or tabs the bills of which are directed upwardly being disposed between the inner 60 and outer folds of the collar. Preferably two of these tabs offset with respect to each other, are provided near each flap and at different levels, the upper tab in each instance being disposed nearer the meeting 65 edge portions of the collar.

Obviously a tie disposed between the folds of the collar and engaged over one or the other of these hooks at each side will be supported when the collar is in place so that it 70 cannot slip down below the collar button. When a tie of light material which will occupy but little space is employed it will be disposed in engagement with the upper tabs, while a bulkier tie will be engaged with the 75 lower tabs. It will be noted that the tabs of the collar are spaced vertically and offset with respect to each other so as to facilitate the insertion of a tie beneath either tab without interference from an adjacent tab. 80 It will also be noted that the base of each tab is spaced from the adjacent wall of the collar so as to produce a clearance and thus permit the necktie to be adjusted on the collar without wedging the tie or causing un- 85 due friction between the tie and collar.

In Fig. 3 of the drawings I have illustrated a modified form of construction in which the inner fold of the collar 16 is formed, adjacent each buttonhole flap with 90 one or more U-shaped clefts 17 corresponding to clefts 14 but having their sides directed downwardly. In this form of my invention the tongues or tabs 18 thus provided are merely bent outwardly to provide hook 95 shaped abutments or tabs which will engage a tie. The method of employment is, of course, the same as that of the collar first described.

In Fig. 4 of the drawings I have illustrated a modified form of construction adapted for use upon wash collars. As there shown the inner fold of the collar 19 is provided with tabs of fabric 20 which are stitched or otherwise secured to its outer 105 face with their free ends directed upwardly to support a tie.

Having thus described the invention, what is claimed as new is:

1. A turn-over collar construction including inner and outer folds, the inner fold at its ends being formed with flaps provided

with buttonholes and adjacent the flaps being formed with substantially U-shaped clefts the sides of which are directed upwardly, the tabs defined by the clefts being 5 bent outwardly and upwardly to provide upwardly directed hooks disposed between the folds of the collar, two of these hooks being formed at each end of the collar and at different elevations.

16 - 2. A collar including a neck band portion

having buttonhole flaps at its ends and vertically spaced upwardly projecting tie-engaging tabs carried by the neck band portion adjacent the end of each flap, the tabs at each flap being offset with respect to each other and spaced from the collar throughout their entire height to produce a clearance for a necktie.

In testimony whereof I affix my signature.
LAWRENCE HENRY TAYLOR. (L.H.T.)
